UNITED STATES PATENT OFFICE

2,267,662

PRESS

Otto O. Miller, Rochester, Ind., assignor of fifty
per cent to Hugh J. Miller, Rochester, Ind.

Application January 25, 1941, Serial No. 376,010

1 Claim. (Cl. 100—19)

This invention relates to new and useful improvements in the art of presses, the principal object of the invention being to provide a high capacity press at the lowest possible cost and without requiring special costly equipment.

Another important object of the invention is to provide a press of the character stated which will be simple in construction and simple to operate.

Other objects and advantages of the invention will become apparent to the reader of the following specification.

In the drawings:

Figure 1 represents a front elevational view of the press.

Figure 2 is a side elevational view.

Figure 3 is a fragmentary vertical sectional view taken substantially on the line 3—3 of Figure 1.

Figure 4 is a horizontal sectional view taken substantially on the line 4—4 of Figure 1.

Figure 5 is a perspective view of one of the work supporting plates.

Referring to the drawings wherein like numerals designate like parts, it can be seen that numerals 5, 5 denote a pair of upwardly converging posts which are bridged adjacent their upper ends by channeled members 6, 6. The lower flanges of the channeled members 6, 6 are bridged by a plate 7.

A channeled member 8 is interposed between the posts 5, 5 a substantial distance below the plate 7 and the ends of this channeled member 8 have downturned tongues 9 riveted or otherwise secured as at 10 to the posts 5.

A pair of guide rods 11, 11 extend downwardly from the plate 7 and through openings in the bottom of the channeled member 8 where they are threaded and equipped with nuts 12.

A hydraulic jack supporting plate 13 having openings in the end portions thereof for receiving the rods 11, 11, is vertically movable on the rods, and compression springs 14 are provided on the lower portions of the rods 11, 11 and

interposed between the channeled member 8 and the plate 13 so as to normally maintain the plate 13 and a hydraulic jack 15 mounted thereon in the elevated position shown in Figure 1.

Extending downwardly from the bottom of the plate 13 is a plunger 16 which extends through an opening in the intermediate portion of the channeled member 8, and when the hydraulic jack 15 is operated, the plate 13 will be moved downwardly, carrying with it the plunger 16 against work supported on slats or plates 17 straddling channeled members 18 bridging the posts 5, 5.

As can be seen in Figure 1, additional channeled members 19 bridge the lower ends of the posts 5, 5 and, of course, these members 19 also furnish a support for work. A pair of transversely extending channeled members 20 serve to define a base for the aforementioned machine.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A press comprising a vertically disposed frame having a top, a work supporting cross member supported by the frame, an intermediate cross member between the work supporting cross member and the top, a pair of guide rods extending from the intermediate cross member upwardly to the top, a plate having openings therein receiving the rods, said plate being slidable on the rods, a plunger depending from the plate, said intermediate cross member having an opening therein through which the plunger is movable, compression springs on the guide rods interposed between the plate and the intermediate cross member, and a jack mounted on the plate and having an extensible element operative against the said top.

OTTO O. MILLER.
